CASTING APPARATUS

James W. McGill, Alcoa, Tenn., assignor to
 Aluminum Company of America, Pittsburgh,
 Pa., a corporation of Pennsylvania

Application October 10, 1942, Serial No. 461,558

6 Claims. (Cl. 22—136)

This invention relates to the casting of ingots and the like and it concerns, more particularly, the casting of ingots in tilt molds.

Because molten metal can be poured into them with a minimum of turbulence, tilt molds have come into wide use, particularly in the casting of ingots of the light metals aluminum and magnesium.

Tilt molds usually comprise two cast iron halves hinged at one side and pivotally fastened to a fixed support at their upper portion. At the beginning of casting operations, they are rotated upon the pivotal support until they are almost horizontally disposed with just enough slope in their mold cavities to permit the molten metal to flow quietly and without agitation toward the lower corner of the mold. As the pouring operation proceeds and the level of the molten metal in the mold cavity rises, the mold is gradually lowered until the mold is in a vertically upright position, at which time the mold cavity is substantially filled.

Usually it is desirable that the mold be at a high enough temperature before the casting operation takes place to prevent the metal from solidifying so rapidly that cavities are formed in the casting. On the other hand, it is desirable that the molten metal be cooled sufficiently rapidly after entering the mold to prevent segregation of alloying elements and to impart a fine grain structure to the cast ingot.

In order to accelerate the cooling of the cast or poured metal, water jackets through which cooling water is circulated are commonly provided in the walls of molds. Such jackets, however, have heretofore been completely filled with water and consequently they have the disadvantage that, instead of cooling the walls of the mold progressively as adjacent portions in the mold cavity are filled with molten metal, they cool the entire wall of the mold simultaneously, causing a heat loss from portions of the mold cavity before they are filled during casting operations.

The present invention has for an object to provide an improved water cooled mold of the tilt type.

More particularly, an object of the invention is to provide a water cooled tilt mold wherein cooling begins adjacent those areas first filled with molten metal and proceeds throughout the mold as the mold cavity becomes filled with molten metal.

A further object of the invention is to provide an improved tilt type mold having a jacket wherein the rise in the level of a circulating liquid

coolant is synchronized with the rise of molten metal being poured into the mold cavity.

Other objects and purposes will appear in the following description of the invention.

5 In accordance with the invention, the side walls of a conventional pivotally supported tilt type mold are provided with a water jacket having an inlet preferably near the base of the mold and an outlet adjacent the mouth of the mold and in proximity to the wall of the mold that is lowermost when the mold is in horizontal position. Water or other liquid coolant enters the jacket through the inlet and fills the jacket to the level of the outlet, the overflow of water escaping 10 through the outlet from the jacket. While the casting operation is taking place and the base of the mold is being lowered to bring the mold to an upright position, the jacket progressively fills with water, becoming completely filled when the 15 casting operation is completed. Since the level of the water in the jacket, as well as the level of the molten metal in the mold cavity, is determined by the angle at which the mold is disposed on its pivotal support, the filling up of 20 the jacket with water and the filling up of the mold cavity with molten metal proceed apace and the side walls of the mold are contacted by water in the jacket at substantially the same time as the level of molten metal reaches adjacent portions 25 in the mold cavity. This provides a uniform rate of cooling throughout the casting operation since the level of coolant in the jacket at all times coincides with the level of molten metal in the mold cavity.

30 35 A preferred embodiment of the invention is illustrated in the accompanying drawings, in which:

Fig. 1 is a plan view of a tilt mold designed for the casting of ingots and adapted to the objects of the present invention;

40 Fig. 2 is a side view of the mold shown in Fig. 1;

Fig. 3 is a sectional view of the mold taken on the line III—III of Fig. 2; and

45 Fig. 4 is a side view partially in section showing the mold during a stage in the pouring operation.

In the drawings, wherein like reference numerals identify similar parts, 1 and 2 represent two 50 mold sections of a mold of cast iron or other suitable material enclosing a mold cavity 2a. The mold sections are joined by a hinge pin 3 passing through suitable aligned bosses or brackets 4 provided along one side of the sections 1 and 55 2. The opposite sides of the two sections are

adapted to be clamped together by a conventional latch mechanism 5 when the mold is closed. At the bottom of the mold, a base plate 6, preferably hollow and water cooled, is provided, and a block 7 projects outwardly adjacent the top of the mold.

Suitably secured to the block 7, as by screws 8, is a horizontally disposed channel member 9 provided at each of its extremities with a laterally turned member 10. Each member 10 is provided with a trunnion 11, the trunnions being disposed in axial alignment and journalled in fixed pedestals or supports 12. This arrangement permits the entire mold to swing about the horizontal axis of the aligned trunnions 11.

Preferably an external lug 13 is provided on base plate 6 having an aperture 14 by means of which a vertical hoisting cable 15 (Fig. 4) can be attached for lifting or swinging the mold to bring the mold from its normal upright position to its inclined position for initial reception of the molten metal therein. The top of the mold is provided with bosses 16 having projecting pins 17 coaxial with the trunnions 11 and upon which a pouring crucible, not shown, may be supported during casting operations.

Each of the mold sections 1 and 2 is provided in its side wall with a water jacket or chamber 18 having communication with the outside of the mold adjacent the top of the mold by a discharge opening 19, which may be formed as a continuous slot across the side of the mold. Preferably a ledge 19a is disposed about the mouth of the mold and above the opening 19 to guard against contact of water issuing from the discharge opening with the metal being poured into the mold cavity. The ledge adjacent the pivotal support is inclined downwardly at 19b to deflect water issuing from the jacket away from the mouth of the mold.

The lower portion of each jacket is provided with an inlet 20, to the inner end of which is connected a distributor pipe 21 that extends across the lower end of the chamber 18. A series or row of perforations 21a is formed in the wall of the pipe 21 through which jets of water issue into the jackets. Preferably the jets of water are directed against the inner wall of the chamber 18. Each jacket also is provided at its lower portion with a pipe having a drain cock 22 outside the mold adapted to be actuated by a rod 23.

In the apparatus illustrated, a water supply line 24 passes centrally through one of the fixed supports 12 and its trunnion 11. The water supply line 24 connects with a downwardly extending conduit 24a, the lower end of the latter being connected to an inlet 25 leading into the hollow base plate 6. Water entering into base plate 6 discharges through drain pipe 26, emptying therefrom into a suitable open drain trough (not shown) below the mold. A flexible hose 27 connects conduit 24a to the inlet pipe 20 for flow of the liquid coolant, preferably water, through the distribution pipe 21 of mold section 1. A pipe 28 passes from conduit 24a around the rear side of the mold to the opposite side of the mold and connects with the inlet 20 of the mold section 2 through a flexible hose 29.

Reference numeral 30 indicates the pools of liquid coolant that are introduced into the jackets 18 while the apparatus is being used for casting operations, and reference numeral 31 denotes the body of metal being cast in the mold cavity 2a.

In the operation of the apparatus, hoisting cable 15 is lifted by a crane or other device, not shown, to swing the mold, the cavity of which is

heated to the desired temperature, from the upright position shown in Fig. 2 to a position but slightly inclined from the horizontal. Before lifting the mold, the drain cocks 22 are opened to empty the water chambers 18. A pouring crucible, not shown, filled with molten metal then is supported upon the pins 17 and the crucible is tilted to pour the metal into the mold cavity. The molten metal flows with a minimum of turbulence down the slight slope formed by the inclined wall of the mold cavity to the lower portion of the mold. As the lower portion of the mold cavity becomes filled, the metal backs up toward the open mouth of the tilted mold, whereupon the mold is gradually lowered about its pivotal support until the cavity is filled, with the mold returned to its upright position.

While the casting operation is taking place, water is delivered constantly through the supply line 24 to conduit 24a and pipe 28 and thence through the hose connections 27 and 29 to the base plate 6 and the distributing pipes 21 in the jackets 18. With the mold in the near horizontal position at the beginning of the pouring operation, the jets of water issuing from the perforated distributing pipes 21 strike the inner side walls of the mold section and form a pool 30 (Fig. 4) in the lower portion of the jackets 18, the overflow of water from the pool 30 escaping out of the slotted discharge openings 19 as is clearly shown in Fig. 4. The pools of water 30 in the respective chambers 18 fill a progressively greater area in the jackets as the mold is lowered to upright position and the level of the water rises in the jackets. Hence, during the entire casting operation, the level of the water within the jackets automatically synchronizes or corresponds with the level of the metal within the mold cavity, and the mold wall is progressively contacted by the water coolant in the jackets simultaneously with the rise of molten metal in the adjacent mold cavity.

The circulation of water through the base block 6 provides a means for cooling the bottom of the mold.

If it is desirable that the coolant contact each portion of the mold wall before or after, instead of at the same time as the level of molten metal arises to adjacent portions in the mold cavity, the mold illustrated herein is susceptible of modification whereby the level of water in the jacket is higher or is lower, as predetermined, throughout the casting operation than the level of the molten metal being poured into the mold. By positioning the lower portion of the discharge opening so that it is closer to the upper side of the mold when the mold is pivoted to horizontal position, the level assumed by the water in the jacket before it overflows through the discharge opening becomes higher with respect to the level of molten metal in the mold cavity. Likewise the lower portion of the discharge opening may be advanced toward the lower side of the substantially horizontally disposed mold, whereby the water assumes a lower level throughout the casting operation with respect to the metal being poured into the mold cavity.

The discharge opening should be sufficiently large to permit escape of a volume of water equal to that being admitted into the jacket through the inlet pipe 20. An opening of such size permits escape of the entire overflow of water from the jacket, no matter what the inclined position of the mold might be, and prevents the jacket

from becoming filled with water above the level of the lowermost portion of the opening.

It will be apparent that the cooling jacket described herein may be employed not only with molds of the specific construction illustrated but also with other types of tilt molds known to the art as well. Also, the apparatus specifically described is susceptible to various modifications, and it will be understood that the various changes and modifications that will be suggested to those skilled in the art are within the scope of the invention as defined in the appended claims.

I claim;

1. The method of cooling a cast article at a progressive and uniform rate during the casting thereof in a tilt mold, which comprises passing a liquid coolant through a jacket in the side wall of said tilt mold during the casting operation as the mold is pivoted from the horizontal to the upright position, and effecting discharge of said coolant from the jacket at a point near the mouth of the mold and adjacent the side of the mold that is lowermost when the mold is in the horizontal position at a rate to cause the level of liquid coolant in said jacket to occupy progressively a greater volume and to rise apace with the rise in the level of the molten metal being cast in the mold cavity as the mold is moved from a tilted to upright position.

2. A tilt mold comprising a body having a cavity therein open at the top for receiving molten metal, means for pivotally supporting said body adjacent to an upper edge thereof, said body having a cooling chamber in at least one side thereof substantially coextensive in area with that of the mold cavity, and an inlet in said chamber for the admission of a liquid coolant and an outlet adjacent the pivotal support of the mold body and of a size sufficient to discharge the coolant at least at substantially the same rate as that at which it is admitted to the chamber whereby the rise in level of the coolant in the chamber substantially coincides with the rise in level of molten metal in the mold cavity as the mold body moves from the initial pouring position to an upright position.

3. A tilt mold comprising a body having a cavity therein open at the top for receiving molten metal, means for pivotally supporting said body adjacent to an upper edge thereof, said body having cooling chambers in opposite side walls thereof substantially coextensive in area with that of the mold cavity, and inlets near the bottom of each of said chambers for the admission of a liquid coolant and an outlet from each of said chambers adjacent the pivotal support of the mold body and of a size sufficient to discharge the coolant at least at substantially the same rate as that at which it is admitted to the chamber whereby the rise in level of the coolant in the chamber substantially coincides with the rise in level of molten metal in the mold cavity as the mold body moves from the initial pouring position to an upright position.

4. A tilt mold comprising a body having a cavity therein open at the top for receiving molten metal, means for pivotally supporting said body adjacent to an upper edge thereof, said body having a cooling chamber in at least one side thereof substantially coextensive in area with that of the mold cavity, and an inlet in said chamber for the admission of a liquid coolant and an outlet consisting of a slot extending across the top of the chamber with one end adjacent the pivotal support of the mold body, said slot being of a size sufficient to discharge the coolant at least at substantially the same rate as that at which it is admitted to the chamber whereby the rise in level of the coolant in the chamber substantially coincides with the rise in level of molten metal in the mold cavity as the mold body moves from the initial pouring position to an upright position.

5. A tilt mold comprising a body having a cavity therein open at the top for receiving molten metal, means for pivotally supporting said body adjacent to an upper edge thereof, said body having a cooling chamber in at least one side thereof substantially coextensive in area with that of the mold cavity, and an inlet in said chamber for the admission of a liquid coolant and an outlet consisting of a slot extending across the top of the chamber with one end adjacent the pivotal support of the mold body, said slot being of a size sufficient to discharge the coolant at least at substantially the same rate as that at which it is admitted to the chamber whereby the rise in level of the coolant in the chamber substantially coincides with the rise in level of molten metal in the mold cavity as the mold body moves from the initial pouring position to an upright position, said mold body having an outwardly projecting ledge across the side and above the outlet slot in the cooling chamber, said ledge overlying the slot whereby any coolant is prevented from splashing upwardly from the outlet.

6. A tilt mold comprising a body having a cavity therein open at the top for receiving molten metal, means for pivotally supporting said body adjacent to an upper edge thereof, said body having a cooling chamber in at least one side thereof substantially coextensive in area with that of the mold cavity, and an inlet in said chamber for the admission of a liquid coolant and an outlet adjacent the pivotal support of the mold body and of a size sufficient to discharge the coolant at least at substantially the same rate as that at which it is admitted to the chamber whereby the rise in level of the coolant in the chamber substantially coincides with the rise in level of molten metal in the mold cavity as the mold body moves from the initial pouring position to an upright position, said chamber having valve means at the bottom thereof for draining it when the mold is in an upright position.

JAMES W. MCGILL.
